CLAIM

The ornamental design for a boat, substantially as shown and described.

DESCRIPTION

FIG. 1 is a side view of the boat of this invention. FIG. 2 is a perspective view as seen from 45° off of the front center line of the boat and from slightly below the boat.

FIG. 3 is a rear perspective view of the boat as viewed along a line corresponding to the bottom center portion of the rear of the boat.

FIG. 4 is a plan view of the boat. FIG. 4 is included to more completely illustrate a boat, showing in this view a basically plain and unornamented boat interior.
